(57) **CLAIM**

The ornamental design for a display screen with graphical user interface for personal digital assistance, as shown and described.

DESCRIPTION

FIG. 1 is a top, front and left side perspective view of a personal digital assistance having a display screen showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a an enlarged view of the display screen with graphical user interface; and,

FIG. 8 is an alternate enlarged view of the display screen with graphical user interface displaying an exemplary image.

The broken line showing of the electronic device illustrates environment, whereas the broken lines showing the display screen and elements of the graphical user interface are for illustrating portions of the article. None of the broken lines form part of the claimed design.
